[57] ABSTRACT

A building construction and method which utilizes

columns and precast concrete, generally rectangular, horizontal floor slabs. A first set of columns is erected at the building site and post-tensioned. Then the horizontal slabs are lifted up and positioned with the corners thereof resting on the upper ends of the columns. In the preferred embodiment, each slab has a vertically extending pin secured to the slab at each corner. After the slabs are positioned on the columns, a locking ring is dropped over the pins with the upper edge of the ring extending above the upper horizontal surface of the slabs. A second series of columns is erected in vertical alignment with the previously erected and post-tensioned columns. Each column in the second series rests on the upper edge of the corresponding locking ring. This arrangement provides essentially a point support for the column which permits very easy vertical alignment of the column. Once the column has been aligned, the space between the bottom of the column and the upper surface of the horizontal slabs is dry packed. After the dry pack has set, the second series of columns is post-tensioned before receiving the next series of horizontal floor slabs. The resulting connection between the column and slabs provides a "semi-rigid" connection which is suitable for use in buildings that are constructed in earthquake zones.

BUILDING CONSTRUCTION AND METHOD OF SAME

This invention relates to building systems in general and, more particularly, to a building system and method which utilizes post-tensioned columns and pre-cast concrete horizontal floor slabs.

Various types of post-tensioned column and slab building systems are known in the art. A representative example of one such system is disclosed in U. S. Pat. No. 3,260,025 issued July 12, 1966 to Van Der Lely for PRECOMPRESSED VERTICALLY STACKED, PRE-FABRICATED BUILDING ELEMENTS. In the Van Der Lely building system, individual column elements are positioned between floor elements with a post-tensioning rod-coupling system extending through the columns and floor elements. Alignment of the column and floor elements is achieved by means of complementary, mating surfaces formed in the columns and floor elements. The resulting rigid connection between the columns and floor elements does not provide the desired relative flexibility for earthquake zone building construction. The Van Der Lely system also requires close tolerance manufacturing of the building elements themselves and, more importantly, accurate on-site assembly techniques with a concomitant requirement of relatively skilled and expensive labor.

It is accordingly a general object of the present invention to provide a post-tensioned, column and slab building construction and method which eliminates the relative disadvantages of the prior art systems.

It is a specific object of the invention to provide a building system of post-tensioned columns and slabs which simplifies the erection process and permits the use of relatively unskilled labor.

It is another object of the invention to provide a building system which does not require close tolerance assembly techniques at the construction site.

It is still another object of the invention to provide a post-tensioned column and slab construction which has a semi-rigid connection between each column and slab.

It is a feature of the invention that various building configurations and floor plans can be accommodated by the building system without sacrificing any of the structural and economic advantages of the system.

It is another feature of the building system that the type of connection between the column and slab greatly facilitates the erection and vertical alignment of the columns by providing essentially a point support for the columns during erection.

These objects and other objects and features of the invention will best be understood from a detailed description of a preferred embodiment thereof, selected for purposes of illustration and shown in the accompanying drawings, in which:

FIG. 1 is a view in perspective, partially broken away, showing a multi-story building constructed with the column and slab system of the present invention;

FIG. 2 is another view in perspective and also partially broken away illustrating the corner placement of four horizontal slabs with respect to an interior column;

FIG. 3 is a view in cross-section depicting the post-tensioning system for one of the interior columns shown in FIG. 1;

FIG. 4 is a detailed view in cross-section of a typical bearing arrangement for the column and slab system;

FIG. 5 is a view in perspective, partially broken away, showing the relationship of an exterior column with the horizontal slabs;

FIG. 6 is a plan view, partially broken away, of an interior column and slab connection showing a slab reinforcing system; and,

FIG. 7 is a view in perspective, partially broken away, illustrating another embodiment of the column and slab connection.

10 Turning now to the drawings and particularly to FIGS. 1 through 6 thereof, there is shown a post-tensioned column and slab building system constructed in accordance with the present invention and indicated generally by the reference numeral 10. The building system utilizes four major components which comprise: a plurality of laterally spaced, vertical columns 12; a plurality of generally rectangular, horizontal slabs 14 which rest on the upper ends of the columns, a post-tensioning system, indicated generally as 16; and a connecting system 18 for connecting the columns and slabs together in a "semi-rigid" connection.

Before discussing the building system components in detail, it will be helpful to briefly describe the general erection techniques employed in constructing the building system of the present invention. Looking at FIG. 1, the first level of columns 12 is erected on a base support or cast-in-place footing and piers (not shown) with the columns positioned in laterally spaced, vertical relationship. After erection, each one of the vertical columns is post-tensioned by means of the post-tensioning system 16. The columns are now ready to receive the first horizontal floor slab system. The generally rectangular horizontal slabs are lifted and placed into position with the corners of the slabs resting on the upper ends of the column. The slabs each have chamfered corners 20 which define a central opening 22 when the slabs are positioned on top of the column as best shown in FIGS. 2 and 6. The central opening 22 provides a space for the post-tensioning system 16 and the column-slab connecting system 18, each of which will be discussed below in detail.

With the horizontal slabs correctly positioned on top of the first level columns, another plurality of laterally spaced columns is erected above the slabs and in vertical alignment with the corresponding first level columns. The second level columns are then post-tensioned and, thereafter, the same erection sequence is repeated for each additional level.

In the preferred embodiment of the present invention, both the columns 12 and four slabs 14 are formed from pre-cast concrete. Edge reinforcements (not shown) are used in the slab to provide a "beam band" within the slab. Representative dimensions for these two major components are as follows: columns, 8 feet long, 14 inches square; slabs, 12 x 18 feet and 8 inches thick.

Referring to the detailed and enlarged cross-sectional views of FIGS. 3 and 4, each column 12 has a centrally located cylindrical tube 24 positioned along the longitudinal, vertical axis of the column. Typically, the tube comprises a 2 inches O.D. galvanized steel tube which defines an interior bore 26 within which is positioned a threaded steel tensioning rod 28. The tensioning rod 28 is threaded at both ends and, as shown in FIG. 4, the upper threaded end of the rod extends through a cast-in-place metal plate 30, a smaller metal bearing plate 32, a post-tensioning nut 34 and into the central open-

ing 22 defined by the slab corners 20. Each column is post-tensioned after erection by tightening the post-tensioning nut 34.

Each column has a grout tube 36 which communicates with the interior bore 26 of the tube 24. A suitable grouting material is injected into the space between the post-tensioning rod 28 and the interior walls of the tube 24 through the grouting tube 36.

An interior threaded coupler 40 is screwed onto the upper threaded end of the post-tensioning rod 28. The coupler 40 is designed to receive the lower threaded end of the post-tensioning rod 28 from the second level column, as shown in FIG. 4. The coupler-tensioning rod system provides a structural connection between the two vertically aligned first and second level columns.

In the preferred embodiment of the invention, the slab corners 20 each rest on a bearing pad 42 which is positioned between the bottom surface of the horizontal slab 14 and the upper end of the column 12. Typically, such a bearing pad can be formed from the material sold under the trade name "FABREEKA".

Looking now at FIGS. 3, 4, 5 and 6, a cast-in C-shaped channel member 44 is located on each corner of the horizontal slabs. A corresponding vertical pin member 46 is welded to the upper portion of the channel member 44. As best seen in FIG. 4, the upper end of the vertical pin member 46 is flush with or if desired, below the upper horizontal surface of slab 14. After the horizontal slabs 14 are positioned with the corners of the slabs resting on the upper end of the column, a vertically open ring 48 is dropped down over the corner slab pins 46 thereby holding the horizontal slabs in a predetermined horizontal position on the top of the columns. This temporary holding of the slabs is desirable from a safety standpoint since it prevents the accidental dislodgement of the slabs from the top of the columns before post-tensioning of the overlying column.

Preferably, the central opening 22 is filled with grouting material before erection of the second level column. The overlying column is lifted into vertical position over the ring and then gradually lowered down until its bottom surface engages the upper surface of the ring element 48. Since the diameter of the ring is approximately 5 inches and the bottom of the column 12 is 14 x 14 inches, the ring 48 acts as a point support for the column 12. This arrangement greatly facilitates the positioning and vertical alignment of the column 12. After the column has been aligned, the space between the bottom surface of the column and the upper horizontal surface of the two horizontal slabs 14 is packed with a dry pack 50 as shown in FIG. 4. The dry pack material conforms to the cavity shape and compensates for any irregularities in the planar bottom surface of the column. Once the dry pack 50 has been forced into position between the slabs 14 and the overlying column 12, the column 12 is post-tensioned by tightening up on the post-tensioning nut 34 (see FIGS. 1 and 3).

The preceding description has been directed primarily to an interior column-slab configuration in which four slabs rest upon the upper end of the column as shown, for example, in FIG. 2. However, it should be understood that in the case of an outside column such as that shown in FIG. 5, only two slabs will rest upon the column and that the locking ring 48 encloses the

corresponding two vertical pins 46 and the post-tensioning rod 28. The joint 52 between the two slabs shown in FIG. 5 is filled with grout after the slabs have been positioned on the column. The joint 52 and the similar slab joints shown in FIGS. 1-4 and 6-7 have been depicted in open form for purposes of clarity. However, in practice the bottom slab edges almost touch each other while the upper edges remain open for pouring in the grouting material.

10 It is also possible to construct the connection shown in FIG. 5 by utilizing a single, generally rectangular slab having no joint 52, but instead, a notch formed in one edge with the two vertical pins 46 secured to each side of the notch. This configuration can be employed to obtain a cantilevered end treatment on a building.

15 It will be appreciated from an inspection of the drawings, and in particular the enlarged cross-sectional view of FIG. 4, that the pin-ring-grout connection between the slabs and columns is a "semi-rigid" connection and that the connection will provide some degree of flexibility when subjected to lateral forces. This type of semi-rigid connection is especially suited for building construction in earthquake zones. Given the lateral loads placed on a building as a result of an earthquake, 20 the semi-rigid connection shown in FIG. 4 will "open" between the dry pack 50 and the overlying column 12 to permit movement or "knee action" between the slabs and columns. The already tensioned column rods 28 will be further tensioned as the rods bend under the lateral load. However, when the load is removed, the tensioned rods 28 will return to their minimum tension condition which is, of course, the post-tensioned straight line configuration shown in the drawings.

25 Looking now at FIG. 6, the column-slab connection is shown in plan view and partially broken away to illustrate the use of a reinforcing rod 54 that is welded to the inside of the corner channel 44 and which extends through a portion of the pre-cast concrete, horizontal floor slab 14. Although the reinforcing rod 54 is not required, it can be used to obtain maximum strength for bearing.

30 Other connection systems can be employed to obtain the desired "semi-rigid" connection between the horizontal floor slabs 14 and the vertical columns 12. Referring to FIG. 7, each slab corner 20 is provided with a generally C-shaped, vertically extending, cast-in-place channel 56. The temporary mechanical attachment of the floor slabs 14 to the vertical column during erection is obtained in the embodiment shown in FIG. 35 7 by means of a threaded hook member or eye-bolt 58. A nut 60 is screwed onto the threaded portion of the eye-bolt 58 so that the nut will fit within the channel 56 when the eye-bolt is dropped over the tension rod coupler 40 as shown in FIG. 7. The nut 60 has an exterior dimension which is larger than the outwardly facing opening of channel 56, but smaller than the inside dimension of the channel. In the operative position, nut 60 is forced against the inside wall of the channel opening by means of a spring 62.

40 Having described in detail a preferred embodiment of our invention, it will be apparent to those skilled in the art that numerous modifications can be made therein without departing from the scope of the invention as defined in the following claims.

45 What we claim and desire to secure by Letters Patent of the United States is:

50 1. A building structure comprising:

1. a first plurality of laterally spaced vertical columns, said first plurality including at least one interior vertical column;
  2. means for post-tensioning each of said first plurality vertical columns;
  3. a plurality of generally rectangular horizontal slabs positioned with the corners thereof resting on the upper ends of said first plurality vertical columns including said interior vertical column;
  4. a vertical pin means secured to each corner of said slabs with at least two of said slabs being positioned in adjacent relation on one of said first plurality vertical columns with the corner vertical pin means thereof positioned in corresponding adjacent relation of the column;
  5. vertically open ring means surrounding said two adjacent vertical pin means for maintaining the corresponding adjacent horizontal slabs within a predetermined range of horizontal positions on the upper end of said column;
  6. a corresponding second plurality of laterally spaced vertical columns positioned above said horizontal slabs and in vertical alignment with said first plurality vertical columns;
  7. means for structurally connecting each pair of vertically aligned first and second plurality columns; and,
  8. means for post-tensioning each of said second plurality vertical columns.

2. The building structure of claim 1 wherein the upper end of said vertically open ring means extends above the upper surfaces of said adjacent slabs and the upper end of each of said vertical pin means whereby one of said vertically aligned second plurality columns rests on the upper end of said ring means.

3. The building structure of claim 2 wherein four of said slabs are positioned in adjacent relation on one of said columns with the corner vertical pin means thereof positioned in corresponding adjacent relation on the column and wherein said vertically open ring means surrounds said four adjacent vertical pin means.

4. A building structure comprising:

  1. a first plurality of laterally spaced vertical columns, said first plurality including at least one interior vertical column;
  2. means for post-tensioning each of said first plurality vertical columns;
  3. a plurality of pre-cast concrete horizontal slabs positioned on the upper ends of said first plurality vertical columns including said interior vertical column; each of said slabs having: a generally rectangular plan configuration with four substantially straight side edges and chamfered corners joining said side edges and resting on the upper ends of said columns; a channel member cast in said slab at each corner thereof with the open portion of the channel member facing inwardly; and, a vertically extending pin secured to the outer face of each of said channel member, with at least two of said slabs being positioned in adjacent relation on one of said columns with the vertically extending pins thereof positioned in corresponding adjacent relation on the column;
  4. vertically open ring means surrounding said two adjacent pins for maintaining the corresponding adjacent horizontal slabs within a predetermined range of horizontal positions on the upper end of said column;
  5. a corresponding second plurality of laterally spaced vertical columns positioned above said horizontal slabs and in vertical alignment with said first plurality vertical columns;
  6. means for structurally connecting each pair of vertically aligned first and second plurality columns; and,
  7. means for post-tensioning each of said second plurality vertical columns.

5. The building structure of claim 4 wherein the upper end of said vertically open ring means extends above the upper surfaces of said adjacent slabs and the upper end of each of said vertical pin means whereby one of said vertically aligned second plurality columns rests on the upper end of said ring means.

6. The building structure of claim 5 wherein four of said slabs are positioned in adjacent relation on one of said columns with the corner vertical pin means thereof positioned in corresponding adjacent relation on the column and wherein said vertically open ring means surrounds said four adjacent vertical pin means.

7. A building structure comprising:

  1. a first plurality of laterally spaced vertical columns, said first plurality including at least one interior vertical column;
  2. means for post-tensioning each of said first plurality of columns, said post-tensioning means including a post-tensioning rod extending vertically through the column;
  3. a plurality of generally rectangular horizontal slabs each having a notch portion formed in one edge thereof, said slabs being positioned with the notch portions thereof resting on the upper ends of said first plurality vertical columns including said interior vertical column;
  4. a vertical pin means secured to each side of said horizontal slab notch portion;
  5. vertically open ring means surrounding the vertical pin means on one slab and the corresponding column post-tensioning rod for maintaining said slab in a predetermined horizontal position on the upper end of said column;
  6. a corresponding second plurality of laterally spaced vertical columns positioned above said horizontal slabs and in vertical alignment with said first plurality vertical columns;
  7. means for structurally connecting each pair of vertically aligned first and second plurality columns; and,
  8. means for post-tensioning each of said second plurality vertical columns.

8. The building structure of claim 7 wherein the upper end of said vertically open ring means extends above the upper surfaces of said adjacent slabs and the upper end of each of said vertical pin means whereby one of said vertically aligned second plurality columns rests on the upper end of said ring means.
